UNITED STATES PATENT OFFICE.

WILLIAM J. HUGHES, OF MASON CITY, IOWA.

WATER PURIFIER FOR STEAM BOILERS.

Application filed December 23, 1924. Serial No. 757,658.

To all whom it may concern:

Be it known that I, WILLIAM J. HUGHES, a citizen of the United States, and resident of Mason City, in the county of Cerro Gordo and State of Iowa, have invented certain new and useful Improvements in Water Purifiers for Steam Boilers, of which the following is a specification.

This invention relates to water purifiers for steam boilers and has for an object the provision of simple and efficient means which can be positively relied upon to remove insoluble impurities from the water and prevent said impurities from being carried off by the steam and deposited in various parts of the boiler and in the machinery to which the steam is delivered.

In the drawings:

Fig. 1 is a transverse section through a standard steam boiler structure showing my water purifying apparatus applied thereto;

Fig. 2 a longitudinal section through the central steam drum of the boiler taken on the line 2—2 of Fig. 1;

Fig. 3 a transverse section on the line 3—3 of Fig. 2;

Fig. 4 a longitudinal sectional view of the sedimentation barrel of the apparatus and its connected pipes;

Fig. 5 a side elevation of a portion of the sedimentation barrel; and

Fig. 6 a transverse section on the line 6—6 of Fig. 4.

In carrying out the invention, a draw-off device is located in the steam drum of the boiler and is so constructed that there will be a static head on it which will ensure a uniform rate of flow of water from the drum at a slight distance below the water level, and throughout the length of the draw-off device. The water removed by the draw-off device is led to a purifying device located below the steam drum. The purifying device is in the form of an inclined settling chamber and the outlet therefrom is connected to the lower end thereof and carried up a suitable distance above and then down to a point below the purifier to create a static head and thereby regulate the rate of flow through the draw-off device and through the purifier. The height of the upwardly extending part of the discharge pipe from the purifier is governed by the boiler rating and is arranged to ensure the draw-

off of water for purification at the same rate or at a somewhat greater rate than that at which it is vaporized within the boiler. The rate of purification of the water is therefore regulated in accordance with the boiler rating. By means of the apparatus herein described the circulation of the necessary volume of water is secured and automatically maintained without the use of a pump or an ejector, and a series of baffle plates may be used in the purifier to aid in throwing down the insoluble impurities.

The arrangement of the purifying chamber and the discharge pipe leading therefrom is such that there is a siphonic effect on the circulation which produces the high velocity in the piping connections required to pass the necessary volume of water through the purifying device.

Referring to the parts by numerals 1 designates a standard steam boiler structure. This structure includes steam drums 2, 3 and 4 located at the top of the boiler, and a mud drum 5 located below the steam drums and in free communication with the steam drums through three banks of tubes 6. Each bank of tubes leads from the top of the mud drum to the bottom of one of the steam drums. The water is introduced as at 7 into the first steam drum 2, flows to the mud drum and rises to the same level in all of the steam drums. The water level in the steam drums is constantly maintained by any suitable standard form of automatic feed regulator. The steam generated in the boiler is conducted from the central drum 3 through a pipe 8 which leads to the machinery to be driven by the steam or to a super-heater, not shown.

In the central drum 3, from which the steam is taken, I mount an insoluble collector 9. This collector is in the form of an elongated trough disposed midway of the sides of the drum and extends longitudinally throughout substantially the length of the drum. The longitudinal sides 10 of the trough converge downwardly and their upper edges are disposed in the same horizontal plane. Extending along the bottom of the trough throughout its entire length is a water conduit in the form of a pipe 11. The pipe 11 communicates with the trough through a longitudinal series of small apertures 12 formed in the pipe. These apertures are spaced along the pipe throughout

the length of the trough and diminish successively in size from one end of the trough to the other. The trough is mounted with its upper longitudinal edges disposed at a 5 depth of approximately one inch below the constant water level of the drum.

A pipe 13 leads from the end of the trough pipe 11 adjacent the smallest of the apertures 12. The pipe 13 extends outside of 10 the boiler structure and is formed adjacent the end of the drum 3 with an upward bend 13' extending the height of the trough. The water rises in this bend and creates a static head which prevents a short circuit in the 15 flow of water from the drum through the pipes 11 and 13 and ensures that no water will flow through the pipe 13 until the trough is full.

The pipe 13 leads downwardly and is 20 connected to a water purifying device 14 located without the boiler structure. The device 14 comprises an elongated cylindrical barrel 15 closed at its ends and disposed at an inclination. Mounted within the barrel 25 15 are a series of spaced baffle plates 16 secured to longitudinally extending rods 17. The rods and the baffle plates are removable from the barrel as a unit when either of the end plates 18 of the barrel is removed and 30 each of the baffle plates is formed with an opening 19 at its lower edge and with a second opening 20 adjacent its upper edge. The pipe 13 delivers into the upper side of the inclined barrel adjacent the upper end 35 thereof and the pipe above its point of delivery is provided with a manually operable cut-off valve 21 normally adjusted to open position.

A blow-off pipe 22 leads from the bottom 40 of the mud drum outwardly of the boiler structure and is provided with a manually operable cut-off valve 23. This valve is normally closed, and connected to the pipe 22, inwardly of the valve is a discharge pipe 45 24 which leads from the upper side of the barrel 15 adjacent its lower end. The pipe 24 is provided with a manually operable valve 25 normally adjusted to open position. The pipe 13, barrel 15, pipe 24 and blow-off pipe 22 thus provide a passage for the 50 water from the steam drum 3 to the mud drum. From the mud drum the water may then flow through the pipes 6 to the three steam drums. As a consequence of the location 55 of the water purifier 14 and its connected pipes outside of the boiler, these parts of the apparatus will be much cooler than the steam drum 3 and will induce a continuous circulation downwardly through the water purifier. The pipe 24 is formed with an upward bend the height of which is proportioned to the rate of circulation through the draw-off device and its piping connections necessary to correspond to the boiler 60 rating. For a high rating a low bend is

used and for a low rating a higher bend.

The interior of the barrel 15 of the purifier forms a sedimentation chamber for retaining the insoluble impurities extracted from the water by the baffle plates. Connected to the under side of the barrel 15, adjacent the lower end of said barrel, is a flush pipe 26 which leads to the blow-off pipe 22 of the mud drum outwardly of the valve 23. This pipe 26 is provided with a manually operable valve 27, normally adjusted to closed position. When it is desired to flush out the barrel 15 and the mud drum, the valves 27, 21 and 23 are opened and the valve 25 is closed. Both the mud drum and the barrel 15 are then simultaneously flushed out through the blow-off pipe 22. If it is desired to flush out the barrel 15 without flushing out the mud drum, the valve 23 is closed. At the lower end of the barrel a 85 transparent indicator is mounted to indicate when it is necessary to flush out the accumulated sedimentation in the barrel. There is also a sample collector 28 mounted at the bottom of the barrel for sampling as in making a test for boiler water concentration. This is done immediately after flushing.

The barrel 15 is supported in its inclined position by means of brackets 29 bolted to the outside wall of the boiler.

A number of decided advantages are obtained by the use of an inclined sedimentation chamber. The inclined arrangement of the barrel exposes its entire length to rising air currents which flow upwardly around the sides of the barrel and tend to quickly cool it. This rapid cooling combined with the pull of gravity due to the inclination of the barrel induces the required circulation of water through the sedimentation chamber without the use of a pump or an ejector. In addition the barrel, when so disposed, provides a long settling travel for the water passing through it, as the sediment will be precipitated along substantially the entire length of the lower longitudinal side of the chamber. This purification of the water along substantially the entire length of its travel through the chamber renders the device extremely efficient, so that the water may be circulated at a comparatively rapid rate and still be thoroughly purified.

As steam is generated in a boiler the insoluble impurities accumulate at and near the surface of the water. This accumulation, if carried off with the steam causes great damage. It causes the steam to go over in belches and prevents the proper operation of the super heaters; causes the plugs to blow out from over heating and the consequent loss of the boiler until it is cooled down and the plugs replaced. In steam turbines the insolubles have a particularly injurious effect. They cause the turbine blades or buckets to fill up and also to become worn

- or cut away from the sand blasting effect. They also cause the throttle valve to stick and render the governor useless. This last effect has caused some of the most disastrous 5 turbine explosions. Still another annoying effect of the water impurities is their interference with the operation of the automatic water feed regulators, causing the water feed to become spasmodic.
- 10 Many efforts have been made to overcome the difficulties stated, but these efforts have failed, largely because the insolubles have been allowed to reach the surface of the water and to form a scum before attempting 15 to remove them. It is then too late to prevent them passing off with the steam. The present invention draws off the impurities before they accumulate at the surface of the water. The collector 9 is placed entirely below the water level, and is so designed that it 20 draws the water from both sides uniformly and continuously throughout the entire length of the steam drum. The water passes simultaneously through all the apertures 12 25 spaced throughout the length of the trough and creates a constant and uniform subsurface current directly into the collector from the entire area of the drum. The apertures 12 in the trough conduit 11 are equally 30 spaced and their combined area is slightly less than the cross section of the conduit. This assists in creating a high velocity in circulation. In order that the flow should be equal through the apertures 12, the bend 13' 35 in the pipe was provided. The static head caused by the water in this bend causes the flow to be evenly distributed over the entire surface at all times.
- The apparatus operates continuously and 40 automatically and with sufficient rapidity, owing to the design of the insoluble collector and the inclined purifier, to keep pace with boilers of the highest rating. The apparatus has been used with a boiler supplying a 45 turbine, with the result that after a period of twelve months service the turbine buckets were found to be free from deposit of any kind and free from sand blast effect.
- 50 What I claim is:
1. An apparatus for purifying the water for a boiler comprising an elongated trough adapted to be arranged within the steam drum of a boiler and to extend substantially the length thereof with its upper longitudinal edges disposed below the water level in the drum; a water draw-off conduit extending along the bottom of said trough; an outlet conduit leading from said draw-off conduit and formed with an upward bend to create a static water head, said draw-off conduit being formed along its length with means for admitting water from the trough into the internal channel of the draw-off conduit substantially evenly throughout the length thereof; a water purifying de-
- vice connected to said outlet conduit and adapted to be located without the boiler structure and below the trough; and a discharge conduit leading from said purifying device and formed with an upward bend to create a static water head. 70
2. An apparatus for drawing off water from the steam drum of a boiler for the purpose of purifying it comprising an elongated trough formed with its upper longitudinal edges in the same plane and adapted to be disposed longitudinally within the steam drum below the water level therein, a water conduit extending longitudinally along the bottom of the trough and formed with a longitudinal series of apertures opening into the trough, said apertures diminishing in size from one end of the series to the other, and a water outlet conduit leading from a point in the said apertured conduit adjacent the smallest aperture and formed with an upward bend extending to substantially the height of the trough to create a static water head. 75 80 85
3. An apparatus for purifying water for a boiler comprising means forming an elongated inclined settling chamber, a water conduit leading to the upper end of said chamber, a plurality of baffle plates spaced longitudinally along the settling chamber and extending transversely across it, the said baffle plates being formed to permit the water and sediment to flow along the lower longitudinal inclined side of the settling chamber and being also formed to permit the water to circulate through them adjacent the upper longitudinal side of the chamber, whereby there will be a progressive settling of sediment along the length of the chamber in the spaces between the baffle plates, and an outlet water conduit leading from the lower end of the settling chamber and formed with an upward bend extending a suitable distance above the settling chamber to create a static head and thereby secure the desired rate of flow through the settling chamber. 90 95 100 105 110
4. An apparatus for purifying water for a boiler comprising an elongated trough adapted to be disposed longitudinally within the steam drum of a boiler with its upper longitudinal edges in the same plane and submerged a slight depth below the water level in the drum, a water conduit extending longitudinally along the bottom of the trough and formed with a longitudinal series of apertures opening into the trough, said apertures diminishing in size from one end of the series to the other, a water outlet conduit leading from the end of said apertured conduit adjacent the smallest aperture and formed with an upward bend extending to substantially the height of the trough to create a static water head, means forming an elongated inclined settling 115 120 125 130

chamber adapted to be located without the boiler structure and below the trough, said outlet conduit having a portion leading downwardly from the plane of said bend to the upper end of the settling chamber, a plurality of baffle plates spaced longitudinally along the settling chamber and extending transversely across it, the said baffle plates being formed to permit the water and sediment to flow along the lower inclined side of the chamber and being also formed to permit the water to circulate longitudinally adjacent the upper side of the chamber, and a discharge water conduit leading from the upper side of the lower end of the settling chamber and formed with an upward bend extending a suitable distance above the settling chamber to create a static head and thereby secure the desired rate of flow through the settling chamber.

5. An apparatus for purifying the water for a boiler comprising an elongated trough adapted to be arranged within the steam drum and to extend substantially the length thereof with its upper longitudinal edges disposed below the water level in the drum, a water draw-off conduit leading from the bottom of said trough and formed with an upward bend adapted to create a static water head and to oppose the pressure tending to force the water from the trough into said pipe, a water purifying device adapted to be located without the boiler structure and below the said trough, said device comprising means forming an inclined settling chamber connected at its upper end with the said draw-off conduit, and a discharge conduit leading from the lower end of said settling chamber and formed with an upward bend extending a suitable distance above the settling chamber to create a static head and thereby secure the desired rate of flow through the settling chamber and through the trough in accordance with the boiler rating.

6. An apparatus for purifying water for a boiler comprising a draw-off conduit adapted to be disposed longitudinally within the steam drum of a boiler and to extend substantially the length of said drum; means forming an inclined settling chamber adapted to be located without the boiler structure and below the steam drum; an outlet conduit leading from said draw-off conduit and adapted to deliver water therefrom to the upper end of said settling chamber, said draw-off conduit and said outlet conduit being formed and arranged to cause a substantially even flow of water into the internal channel of the draw-off conduit throughout its length; and a discharge conduit leading from the lower end of the settling chamber.

7. An apparatus for purifying water for a boiler, comprising a draw-off conduit

adapted to be disposed longitudinally within the steam drum of a boiler and to extend substantially the length of said drum; means forming an inclined settling chamber adapted to be located without the boiler structure and below the steam drum; an outlet conduit leading from said draw-off conduit and adapted to deliver water from the draw-off conduit to the upper end of the settling chamber, the said draw-off conduit and the said outlet conduit being formed and arranged to cause a substantially even flow of water into the internal channel of the draw-off conduit throughout the length of said channel; and a discharge conduit leading from the lower end of the settling chamber and formed with an upward bend to create a static water head.

8. An apparatus for purifying the water for a boiler comprising an elongated trough adapted to be arranged within the steam drum of a boiler and to extend substantially the length of said drum with its upper longitudinal edges disposed below the water level within the drum, a water draw-off conduit extending along the bottom of said trough; a water purifying device adapted to be located below the steam drum; an outlet conduit leading from said draw-off conduit and adapted to deliver water therefrom to the said purifying device, the draw-off conduit and the said outlet conduit being formed to cause a flow of water into the internal channel of the draw-off conduit substantially evenly throughout the length of said channel; and a discharge conduit leading from the purifying device.

9. An apparatus for purifying water for a boiler, comprising a draw-off conduit adapted to be disposed longitudinally within the steam drum of a boiler and to extend substantially the length of said drum; a water purifying device adapted to be located below the steam drum; an outlet conduit leading from said draw-off conduit and adapted to deliver water therefrom to the said purifying device, said draw-off conduit and said outlet conduit being formed and arranged to cause a substantially even flow of water from the steam drum into the internal channel of the draw-off conduit throughout the length of said channel; and a discharge conduit leading from the purifying device.

10. An apparatus for purifying the water for a boiler, comprising a draw-off conduit adapted to be arranged longitudinally within the steam drum of a boiler and to extend the greater portion of the length of said drum, said conduit being formed with a longitudinal series of apertures opening into the drum and diminishing successively in size from one end of the series to the other; a water purifying device adapted to be lo-

cated without the boiler structure and below the steam drum; a conduit leading from a point in the draw-off conduit adjacent the smallest of said apertures to said purifying device and adapted to co-operate with said apertures in the draw-off conduit to admit water from the steam drum into the draw-

off conduit substantially evenly throughout its length; and an outlet conduit leading from the purifying device.

In testimony whereof I hereunto affix my signature.

WILLIAM J. HUGHES.
